UNITED STATES PATENT OFFICE.

GEORGE C. MURRAY, OF CHICAGO, ILLINOIS, ASSIGNOR TO KEYOKE RAILWAY EQUIPMENT COMPANY, A CORPORATION OF DELAWARE.

DRAW-BAR YOKE.

1,153,242.

Specification of Letters Patent. Patented Sept. 14, 1915.

Application filed August 17, 1911. Serial No. 644,586.

To all whom it may concern:

Be it known that I, GEORGE C. MURRAY, a citizen of the United States, residing at Chicago, in the county of Cook and State of Illinois, have invented certain new and useful Improvements in Draw-Bar Yokes, of which the following is a specification.

The object of my invention is to provide an improved form of yoke for railway car draft riggings, the form of yoke herein described and claimed being especially adapted for use with the type of draft riggings known as tandem draft riggings, in which two draft springs lying in the same longitudinal line and separately operated upon by the draft and buffing forces are employed.

The object of my invention more particularly is to so construct the draft rigging that the draw-bar may be readily detached therefrom without disturbing the draft rigging, and so that in case of necessity the draft rigging may be removed from the yoke with the minimum amount of disturbance to the other parts of the mechanism.

In the drawings, Figure 1 is a side view partially in section of a tandem draft rigging having my improved yoke applied thereto. Fig. 2 is a perspective view of the upper member of the yoke. Fig. 3 is a perspective view of the lower member of the yoke. Fig. 4 is a cross sectional view on the line 4, 4 of Fig. 1. Fig. 5 is a horizontal sectional view upon an enlarged scale of the structure shown in Fig. 1.

Referring to Fig. 5, which best illustrates the operation of the tandem draft rigging to which my improved yoke is adapted to be applied, the cheek plates 1 are secured by riveting or otherwise to the inner faces of the draft sills 2 and are provided with what may be termed buffing stops 3, 4, 5, and 6 and with draft stops 7, 8, 9 and 10. The draft rigging as an entirety may be supported in any preferred manner not illustrated. Followers 11, 12, 13 and 14 lie between the cheek plates and are free to move within the limits defined by the stops referred to. Draft spring 15 lies between the followers 11, 12 and draft spring 16 between the followers 13 and 14. The yoke designated as an entirety by the numeral 17 surrounds the entire draft rigging and is provided midway its ends with a bridge 18 rigid therewith and designed to coact with the inner followers 12, 13. The inner end of the

draw-bar 19 coacts directly with the follower 11 and is connected by means of the key 20 with the outer end of the yoke 17, the form of such connection being described more fully below. As will be readily understood, upon a buffing strain the draw-bar 19 moves inwardly carrying with it the follower 11 and yoke 17, of which the bridge 18 is a part, and the bridge 18 acts directly upon the follower 13. The buffing blow is thereby restrained by the cumulative resistance of the springs 15 and 16, the followers 12 and 14 at this time remaining stationary against the buffing stops 6 and 4. Upon a pulling strain the reverse action takes place. The general operation of tandem draft riggings of this type being well understood by those familiar with the art, further explanation is unnecessary. It has heretofore been customary to construct the bridge 18 of a separate block of metal held in place by means of bolts, but in my improved yoke I find that a decided improvement is effected by constructing the bridge-piece integral with the yoke, the peculiar construction of my yoke rendering such integral construction possible.

The draw-bar 19 is as usual provided with an enlarged butt end 21 forming shoulders 22 with which the inturned ends 23 of the yoke coact. The yoke in the form illustrated in Figs. 1 to 5 consists of two members 24 and 25 connected at their inner ends by some form of hinged connection 26, the precise form of this connection being immaterial, provided that it admits of a turning movement between the members 24 and 25 without the actual separation thereof. Intermediate the ends of the members 24 and 25 I provide inward projections 26, 27, which may be cored out at 28 to save material and to make the structure lighter. A cross-bolt 29 threaded and provided with a nut 30 serves to secure the yoke members together at their central parts and to prevent them from bending outwardly under excessive strain. In a sufficiently heavy construction, however, such a bolt might be found unnecessary. The bolt hole in the lower yoke member 25 is preferably elongated somewhat longitudinally, as indicated at 31, in order to permit the lower yoke member to be turned upon the hinge 26 without binding upon the bolt. At its outer end the yoke member 24 is provided with

depending ears 32 having apertures 33 designed to receive the key 20. The lower yoke member 25 is provided with upwardly extending ears 34 provided with key apertures 35. The ears 34 are preferably deflected outwardly and formed upon their inner faces with shoulders 36 in order that when the structure is assembled the ears 32 may lie inside of the ears 34 with their lower 10 edges abutting against the shoulders 36.

When it is necessary to replace the draw-bar 19 it is necessary only to withdraw the key 20 from the structure as illustrated in Fig. 1 and to unscrew the nut 30 upon the bolt 29, thereby permitting the lower yoke member 25 to be moved downwardly upon its hinge 26 sufficiently to release the shoulders 22 upon the draw-bar from the inwardly projecting ends 23 of the yoke members. The bolt 29 may, if desired, be long enough so that the nut 30 can be loosened sufficiently to permit the downward movement of the yoke member 25 without removing the nut from the bolt. If it becomes necessary to replace the draft springs or other parts of the draft rigging this can likewise be done without disturbing the upper yoke members and without disconnecting the upper and lower yoke members.

30 While I have described a specific embodiment of my invention, it will be apparent that the principle thereof can be applied in practice without adhering to the precise form of mechanism illustrated.

35 I claim:

1. In a device of the class described, a

yoke comprising two members hinged together at one end and provided at the opposite end with apertured ears adapted to overlap and receive a key when said yoke is closed, and abutments integral with the arms of said yoke intermediate its ends and adapted to coact with a draft rigging contained within said yoke.

2. In a device of the class described, a 45 yoke comprising two members hinged together at one end and provided at the opposite end with inwardly projecting shoulders adapted to coact with outwardly projecting shoulders on a draw-bar and also 50 provided at said opposite end with apertured ears adapted to overlap when said yoke is closed and receive a key passing through said ears and draw-bar, and abutments integrally formed with said members 55 and projecting inwardly of said yoke, said abutments being adapted to coact with a draft rigging contained within said yoke.

3. In a device of the class described, the yoke members 24, 25 connected at one end by the hinge 26 and provided at the opposite ends with the inturned ends 23 and also provided at such opposite ends with the ears 32, 34 having apertures 33, 35 therein, abutments integral with the yoke arms, and a 60 bolt connecting said abutments.

In testimony whereof, I have subscribed my name.

GEORGE C. MURRAY.
